UNITED STATES PATENT OFFICE.

DAVID D. GORDON, OF CHICAGO, ILLINOIS, ASSIGNOR TO THE YOST ELECTRIC MANUFACTURING COMPANY, OF TOLEDO, OHIO, A CORPORATION OF OHIO.

CONNECTING DEVICE.

1,146,325.

Specification of Letters Patent. Patented July 13, 1915.

Application filed February 28, 1913. Serial No. 751,190.

To all whom it may concern:

Be it known that I, DAVID D. GORDON, a citizen of the United States, residing at Chicago, in the county of Cook and State of Illinois, have invented a certain new and useful Improvement in Connecting Devices, of which the following is a full, clear, concise, and exact description, reference being had to the accompanying drawings, forming a part of this specification.

My invention relates to connecting devices and has for its object the provision of an improved device of this character which is more particularly an improvement over my Patent No. 1,041,066.

My invention contemplates a connecting device for electric circuits which may be very advantageously used in connection with so called plugs, and I will describe my invention herein as particularly applied to such a plug.

In my said patent I use a plug portion having within it a plunger, which plunger acts upon a movable element when the plug is inserted in the socket in such a way as to hold the plug in place, this movable element serving at the same time as a current conducting element to establish circuit conditions between the plug and the socket.

In my present invention I have increased the amount of conducting surface between the plug and the screw threaded portion of the socket, and I use a movable element controlled by a plunger for locking purposes only.

My invention, of course, is capable of other application and by specifically describing it as applied to a plug herein, I do not limit myself to such specific arrangement.

I will describe my invention more in detail by referring to the accompanying drawing illustrating the same as applied to a plug, in which:

Figure 1 shows a plug in longitudinal section as applied to a socket, which is partly in longitudinal section; Fig. 2 is a side view partly in section of my improved plug, and Fig. 3 is a perspective view of the plunger. Fig. 4 is a transverse sectional view through Fig. 2.

Referring more particularly to the drawing, I show a socket 1 which may be provided with the customary key 2, and which has a central contact member 3 and an out-

side annular screw threaded contact member 4. My plug is adapted for engagement with this socket and is adapted to contact with the elements 3 and 4, therefore when said plug is inserted in place.

The plug consists of a base portion 5 having the cylindrical extension 6, within which cylindrical extension a plunger 7 is adapted to reciprocate. This plunger carries a contact element 8 which is adapted to engage a contact element 3, and this contact element 8 is held in place by a screw 9 which engages a contact portion 10 at the rear end of this plunger. This contact member 10 has a pocket 11 within which sits a coiled spring 12, the opposite end of which coiled spring sits in a pocket 13 provided in a contact element 14 carried by the base portion 5. The tube 6 of the base portion also has a contact member 15 which through the agency of the conducting element 16 connects with the binding post 17. Suitable wires 19 and 18 lead to the contact elements 14 and 16 respectively, thus to provide a conducting means to the elements 8 and 15. The side of the plunger opposite to that which carries the contact element 15 has a recessed portion 20 in the form of a valley which is adapted to work in conjunction with a locking element 21, herein shown as a sphere. This element 21 is held between this valley portion and between inclined walls 22, 22 of the tube portion 6. Slot 23 is provided in this tube portion so that a screw 24 may be inserted to define the movements of the plunger and also to lock the parts together after assembling. The element 21 is confined between the walls 22, 22 so that it cannot fall out. When the plug is as shown in Fig. 2, the ball 21 rests in the valley and does not protrude beyond the outside contour of the tube 6. When however the plug is inserted in the socket as shown in Fig. 1, the base portion is pressed in farther than the plunger, against the action of the spring 12, and the ball 21 then rides upon the incline of the valley portion 20 so that it engages the screw threaded element 4. A slight turning movement of the entire plug then locks all of the parts securely in position. A very efficient contact is thereby established between the screw threaded element 4 and the contact element 15, and the contact elements 3 and 8; the element 21 is merely used for locking purposes. It will

be seen that adequate conducting surface is thus provided between the various elements and proper facilities are afforded for locking the plug in place after insertion.

5 Having thus described one form which my invention may take, I do not wish to be limited to the precise construction and arrangement herein set forth, but

Having thus described one form of carrying out my invention, what I claim as new and desire to secure by Letters Patent is:

10 1. A plug having a base portion and a plunger, a contact element carried by the plunger, a fixed contact element provided upon said base portion, said contact elements being adapted for engagement with the conducting portions of an internally screw threaded socket, said fixed contact element being of a width to span the space between apices of said screw threaded socket, a locking device provided upon said base portion on the opposite side of the fixed contact element carried by said base, and means whereby said plunger when moved inwardly toward said base portion moves said locking device outwardly, thereby to engage the inner contact portion of the socket and move the fixed contact element into engagement with the inner conducting portion of the socket and lock the plug in position, said fixed contact extending throughout a substantial portion of the periphery of said base.

15 2. A plug having a base portion and a plunger, a contact element carried by the plunger, a fixed contact element provided upon said base portion, said contact elements being adapted for engagement with the conducting portions of an internally screw threaded socket, said fixed contact element being of a width to span the space

between apices of said screw threaded socket, and means controlled by the plunger for locking the plug within the socket.

3. A plug having a hollow cylindrical base portion, and a plunger movable therein, a contact element carried upon the free exposed extremity of the plunger, a fixed contact element provided upon the outer annular surface of the base, said contact elements being adapted for engagement with the central and inner screw threaded contact portions of a socket, said fixed contact element being of a width to span the space between apices of said screw threaded socket, a locking device provided upon said base portion on the opposite side of the fixed contact element carried by said base, and means whereby said plunger when moved inwardly toward said base portion moves said locking device outwardly, thereby to engage the inner contact portion of the socket and move the fixed contact element into engagement with the inner conducting portion of the socket and lock the plug in position, said fixed contact extending throughout a substantial portion of the periphery of said base.

In witness whereof, I hereunto subscribe my name this 26th day of February A. D., 1918.

DAVID D. GORDON.
